UNITED STATES PATENT OFFICE

KENNETH S. JOHNSON, OF SAYLESVILLE, RHODE ISLAND

REGISTERING DEVICE

Application filed June 20, 1930. Serial No. 462,476.

This invention relates to a registering device, and has for its object to provide a single unit which will indicate the amount of operation of the machine such as the total revolutions or output of work, and the periods of time during which the machine is in operation.

A further object of the invention is to provide a device which will indicate the periods of time during which the machine is in operation without vibration of the casing of the device, but rather by a movement independent of the casing received from a moving part, the behavior of which is desired to record.

15 A still further object of this invention is to operate in a single unit a counting mechanism and a recording mechanism both from a common driving shaft.

20 A still further object of this invention is the provision of mounting means for the unit such that the unit may be opened up to expose a chart within for reading or replacement without disturbing the driving connections.

25 With these and other objects and advantageous features in view, the invention consists of a novel arrangement of parts more fully disclosed in the detailed description following, in conjunction with the accompanying drawings, and more particularly set forth in the appended claims.

In the drawings:

Fig. 1 is a face view, partly broken away, of one side of the casing showing the reading of the counting mechanism;

Fig. 2 is a central sectional view through the casing on substantially line 2—2 of Figure 1;

Fig. 3 is a section on line 3—3 of Figure 1 showing the marker and its mounting;

Fig. 4 is a face view of a chart which is operated upon by the marker; and

Fig. 5 is a plan view of the coupling member for attaching the device to a rotary shaft.

45 In the operation of machinery where efficiency is desired to be figured, it is desirable to learn the periods of time during which the machine is in running operation, and the periods of time in which the machine is stopped, both as to duration and as to the time

of day of the occurrence of the periods; it is also desirable to learn the total volume of output of work of the machine which is dependent upon the revolutions thereof. These results are particularly desirable in connection with textile finishing machinery where it is desired to know the number of yards of cloth running through the machine, also periods of time during which the machine is in operation and stopped. Machines of this character must be run at varying rates, depending upon the quality and kind of goods worked upon. The speed at which greatest efficiency is obtained is a predetermined factor. The operator is instructed as to the speed the machine should run in order to obtain the best quality of work, and it is desirable, as a check, to learn that the machine has been run at the predetermined most efficient speed consistent with best quality, and also the periods of operation and inoperation thereof. The output of these machines varies with the revolution of some shaft, and in order to provide a more improved device requiring but a single installation, I have incorporated in a single unit the time recording device and the counting device; and the following is a detailed description of the present embodiment of this invention, illustrating the preferred means by which these advantageous results may be accomplished.

With reference to the drawings, 10 designates one part of the casing, and 11 the other part which are each formed with hinge eyes and hinged together by hinge pintle 12. An opening 13 is provided in the base of the casing part 10 to receive a mounting support for retaining the same in stationary position upon the desired part of the machine. In the casing part 11 I have mounted a continuous rotating mechanism or clock work housed in its casing 14 and held in the part 11 by suitable screws 15. The clock mechanism causes continuous rotation of the scalloped disk 16 upon which there is mounted a chart 17 by binding means 18. The part 11 is swung about the part 10 to open position to expose the binding means 18 and the chart 17 for inspection or removal and replacement, as desired. The binding means 18 also serves as a wind-

ing knob for the spring of the clock mechanism contained in the casing 14.

The casing 11 is held in closed position, as illustrated in Figure 2, by means of an eccentrically mounted disk 19 which may be swung into the slot 20 in the pin 21 which extends through the opening 22 in the part 11 and which is fixed in the part 10. This disk 19 is pivoted at 23 and is operable by means 10 of a handle portion 24 to swing the cam 19 about its pivot into or out of the slot 20. Cam 24 may be locked in securing position by means of a padlock extending through an opening in the handle 24, and the opening 25 15 in the ear 26 of casing 11.

When the casing parts are in closed position, the rotating chart 17 engages a marker 27 which is in the form of a pencil or a stylus to operate over a specially prepared chart 20 indicating its movement thereon. The marker 27 is mounted upon a member 28 and is shaped to avoid contact with the knob 18 pivoted at 29 and having a bifurcated portion 30, which straddles the eccentrically mounted 25 pin 31 rotated by a shaft 32 having a bearing in the part 10 and operated by a worm gear 33 and worm 34 on the drive shaft 35 which extends across the casing parallel to the bore 13 for mounting the same. The shaft 35 projects through the casing and is suitably connected as at 36 with a member 37 adapted to be connected to the end of a rotating shaft, the behavior of which it is desired should be indicated by the registering device. Holes 35 may be drilled in the end of such shaft, and the portions 38 of the member 37 inserted into these holes in order to insure a positive connection.

The counting mechanism is also driven 40 from the shaft 35 by means of a worm 39 mounted thereon, worm gear 40, worm 41 and gear 42 to operate the counting mechanism and register by suitable digit disks 43 the output of the machine or the number of revolutions of the shaft to which it is connected.

The counting mechanism permits of wide 45 flexibility of gearing for varying machines to obtain the reading in yards of goods passing through the machine or any other desired unit of measure.

The casing part 10 is so mounted that the 50 reading 43 is exposed to view at all times and the parts so related that the part 11 which is hinged to the part 10 is free to open 55 by manipulation of the member 19 to expose the chart 17 for inspection or removal.

Upon rotation of the shaft 35, the counting 60 mechanism operates to register the amount of operation of the machine, such as yards of work passing therethrough, to which 65 the drive shaft 35 is connected, and at the same time the eccentric 31 causes an oscillating movement of the member 28 which may be shaped as illustrated, or any other desired 70 shape to oscillate the marker during the

movement of the shaft and draw a wavy line 44 on the chart, as indicated in Figure 4. When the shaft, the behavior of which is being indicated, stops, a straight line will be recorded 45 due to the continuous turning of the chart 17 by the clock-work 14, and upon resuming operation again, the wavy line 44 will be made and so on, thus indicating to the observer of the chart in Figure 4 that the machine is in operation from 75 the hours 7 to 8 in the morning, stopped from 8 to 8:50, running from 8:50 to 9:10, stopped from 9:10 to 9:20, running from 9:20 to 10:40, stopped from 10:40 to 11:00, running from 11:00 to 12:00, stopped from 12:00 noon 80 to 1:00 o'clock, etc.

The mechanism communicating these desirable results are all contained within a single casing which is portable as a unit and adapted to be applied to any machine, the 85 operation of which is desired to be learned, both registering mechanisms being driven from a single drive shaft in the casing.

While I have described certain construction forms which embody the principles of 90 my invention, it is obvious that other desired changes in arrangement may be made within the spirit and the scope of the invention as defined in the appended claims.

I claim:

1. A registering device comprising a casing, a drive shaft in said casing, means to connect said drive shaft to a rotary part, a rotatable chart, a pivotally suspended mounting provided with a marker to cooperate with said chart and having a slot 100 therein, and eccentric means in said slot responsive to the movement of said drive shaft to operate said marker.

2. A registering device comprising a casing, a drive shaft in said casing, means to connect said drive shaft to a rotary part, a rotatable chart, a pivotally suspended mounting provided with a marker to cooperate with said chart and having a slot therein, a disc member rotatable about its center, a pin in said slot and mounted on said disc at a point spaced from the center thereof, and gear means connecting said drive shaft and disc, whereby to transmit movement of 110 said drive shaft to said marker.

3. A registering device comprising a casing, a drive shaft in said casing, means to connect said drive shaft to a rotary part, a rotatable chart, a pivotally suspended mounting provided with a marker to cooperate with said chart and having spaced engaging surfaces, and eccentrically movable means alternately engaging said surfaces to swing said mounting about its pivot, said eccentric means being responsive to the movement of said drive shaft to operate said marker.

In testimony whereof I affix my signature.

KENNETH S. JOHNSON.
